UNITED STATES PATENT OFFICE.

TAYLOR J. SMITH, OF UNION CITY, GEORGIA, ASSIGNOR OF ONE-HALF TO CHARLES H. GULLATT, OF UNION CITY, GEORGIA.

TRUSS.

Application filed October 16, 1924. Serial No. 744,068.

To all whom it may concern:

Be it known that I, TAYLOR J. SMITH, a citizen of the United States, residing at Union City, in the county of Campbell and 5 State of Georgia, have invented new and useful Improvements in Trusses, of which the following is a specification.

This invention relates to surgical appliances and has for its general object the construction of an abdominal truss embodying novel features by means of which sanitation and comfort are promoted and which will 10 efficiently support a rupture.

More specifically, certain of the objects 15 of the invention are to provide a truss which, while affording adequate support to the rupture, offers a minimum of resistance to the respiratory movements of the abdominal wall; which is so constructed and 20 arranged that it will slip neither upwardly nor downward from the position to which it is adjusted, and which is cool, perfect in fit, and easily cleaned.

Another object of the invention is to construct a belt supported truss having a body-engaging member capable of partaking of 25 the movements of the abdominal wall without hindrance from the belt.

Still another object of the invention is 30 the provision of a truss having means which automatically engage the skin in a massaging action through the normal movements of the abdomen.

Other objects of the invention will appear 35 as the description of the preferred embodiment thereof proceeds.

In the drawings:—

Figure 1 is a perspective view showing a preferred form of my improved truss.

40 Figure 2 is a similar view, parts of the outer member being broken away.

Figure 3 is a section taken along the line 3—3 of Figure 1.

Figure 4 is a section taken along the line 45 4—4 of Figure 1.

Figure 5 is a front elevation of the hinged pressure plate.

Figure 6 is a front elevation showing one of the body-engaging plates.

50 Figure 7 is a front elevation of the supporting plate.

Figure 8 is a perspective view showing a slightly modified form of the invention.

Referring now in detail to the several 55 figures, and first, to the embodiment of the

invention illustrated in Figures 1 to 7 inclusive, the numerals 1 and 2 represent body-engaging plates, which in the illustrated form of the invention are shown as being symmetrically shaped with respect to 60 the median line of the truss. The body-engaging plates are formed on that side which contacts with the body, with a curvature which conforms to the normal shape of the abdominal wall in the region to which 65 the truss is applied. The edges of the body-engaging plates are rolled outwardly as shown at 3 in Figure 4 so as to avoid the presence of sharp edges which might 70 press into the abdominal wall, and cause discomfort. The body-engaging plates as 75 well as the other structural parts of the truss, with the exception of the belt, are preferably made from metal and are perforated as shown at 5 for the purpose of rendering them cool and self-ventilating and causing the skin to slightly protrude through the holes, thus causing the truss 80 to stick at the place desired and to massage the affected parts through normal movements of the abdominal wall. In this way the truss helps nature in strengthening the muscles that have weakened.

The body-engaging plates 1 and 2 are adjustably secured to the back of the hinged pressure plate 6. Said pressure plate is slightly concave on its inner side to suit the contour of the body and is formed with slots 7 and 8, extending preferably in a horizontal direction, through which pass the 85 shanks of studs 9 and 10 the latter, as shown in Fig. 4, having heads 27 which seat in countersunk recesses in the body-engaging plates so as to lie flush with the surface of said plates. Thumb nuts 11 and 12 are screwed upon the projecting ends of 90 said shanks and serve to hold the body engaging plates rigidly in place. Upon loosening said nuts the body-engaging plates may be laterally adjusted. The 95 value of this adjustment is that the wearer is enabled to adjust the truss to his body. By making correct adjustment, a perfect fit is obtained so that a single size of truss may be used universally, obviating the necessity for taking measurements, which are frequently inaccurate, resulting in misfit 100 trusses.

The pressure plate 6 is hingedly suspended 110 from the supporting plate 13 by means

of hinges 14 and 15 carried jointly by said pressure plate and by the arms 16 and 17 of the plate 13. The lower part of said supporting plate is preferably formed with 5 lateral eyes 18 for the retention of the belt hooks 19. The pressure plate and the supporting plate are provided with registering spring supports 22 and 23 on opposite sides of the median line of the truss between 10 which support the springs 24 and 25 are arranged, said springs being under compression and therefore urging the pressure plate with the body-engaging plates in a direction toward the body.

15 It will be noted that while the hinges from which the pressure plate is suspended are positioned adjacent the upper edge of said pressure plate, the belt is carried adjacent the lower portion of said pressure plate, an arrangement which gives to the pressure plate quite a freedom of movement. For instance, slight pressure of the abdominal wall against the upper part of the body-engaging plates 1 and 2 is transmitted without substantial resistance to the hinged end of the pressure plate and supporting plate causing said end to freely rock about some point in or below the zone of the belt, as a fulcrum, imposing but 20 slight pressure upon the abdominal wall, adjacent the hinged ends of said plates and permitting its free and unimpeded movement. At the same time the pressure of the springs 24 and 25 against the lower portions of the body-engaging plates holds the latter snugly in position above the rupture, with sufficient tension to inhibit any tendency of the abdominal wall to bulge locally, but not so tightly as to prevent movement of the abdominal wall as a whole. A 25 chain or other suitable means 20, attached to the lower edge of the supporting plate and to the pressure plate, limits the range of movement of the supporting plate when 30 the belt is unfastened preventing escape of the springs.

The function of the belt 26 is to sustain 35 the supporting plate in position, but the belt is, in turn, supported by the truss, for the 40 shape of the body-engaging plates, the perforations therein, and the influence of the springs 24 and 25 thereupon cause said plates to adhere closely to that portion of the body to which they are applied, thus 45 effectively preventing the shifting of said body-engaging plates. As the pressure plate is rigidly secured to said body-engaging plates, and the supporting plate is rigidly connected to the pressure plate the 50 fixity of the body-engaging plates assures the maintenance of the belt in its normal 55 position.

Another function of the belt is to increase 60 or decrease the tension of the springs 24 and 25 according to whether the belt is

tightened or loosened. The belt is preferably made adjustable by any means commonly in use, such as glove fastener 21, so that when the circumference of the belt is diminished said springs are compressed, 70 thus increasing their tension. Ordinarily, however, the belt is adjusted to a pressure just sufficient to hold the parts in place, the normal tension of the springs 24 and 25, and the holes in the body-engaging 75 plates being relied upon to hold the body-engaging plates in place as well as to yield to the respiratory movements of the abdominal wall. A truss, having inherent features which cause it to rest so lightly upon the affected parts prevents weakening of the muscles of the abdominal wall and therefore maintains the parts in a condition most conducive to healing or natural 80 repair.

85 Although it is preferred to make the several parts of the truss, with the exception of the belt, of metal, such as aluminum, it may obviously be made of any suitable substance such as pyralin or any of the well-known phenolic condensation products without departing from the scope of the invention.

90 In the modified form of the invention 95 shown in Figure 8 I have omitted the separable pair of body-engaging plates 1 and 2 and permit the pressure plate to come into direct contact with the abdominal wall. To this end the pressure plate has been enlarged and given a shape to conform closely to that of the surface against which it is to be applied. Aside from the omission of the generally desirable feature of lateral adjustability, such as is present in the first 100 form of my invention, the latter modification 105 does not vary therefrom in any essential particular.

110 Although I have shown and described what I consider to be very practical forms 115 of my invention, it is to be understood that the scope of the invention includes the making of any alterations or additions or substitution of equivalents such as may be within the province of one skilled in the art to which the invention appertains, restricted only by the express limitations defined in the claims.

115 Having described my invention what I claim as new and desire to secure by Letters Patent, is:—

120 1. A truss, comprising a supporting member, means for securing said supporting member to the body, a body-engaging member hingedly attached to said supporting member above said securing means, and resilient means between said body-engaging member and supporting member in the zone of said securing member.

125 2. A truss, comprising a supporting member, a belt for securing said supporting 130

member to the body, a body-engaging member hingedly attached to said supporting member above the zone of said belt, and resilient means between said body-engaging member and supporting member in the zone of said belt, said resilient means being normally maintained under compression by said belt.

3. A truss, comprising a supporting member, a belt for securing said supporting member to the body, a body-engaging member hingedly attached to said supporting member above the zone of said belt, and resilient means between said body-engaging member and supporting member in the zone of said belt, said resilient means being normally maintained under compression by said belt, said belt being adjustable for varying the compression of said resilient means.
4. A truss, comprising a supporting member, means for securing said supporting member to the body, and a body-engaging member comprising a pressure plate hingedly attached to said supporting member above said securing means and separate body-engaging plates secured to said pressure plate.

5. A truss, comprising a supporting member, means for securing said supporting member to the body, and a body-engaging member comprising a pressure plate hingedly attached to said supporting member above said securing means and separate body-engaging plates adjustably secured to said pressure plate.

6. A truss, comprising a supporting member, means for securing said supporting member to the body, a body-engaging member including a pressure plate hingedly attached to said supporting member above said securing means, laterally adjustable body-engaging plates, and means for securing said

plates to said pressure plate in various positions of lateral adjustment.

7. A truss, comprising a supporting member, provided with belt-retaining means, a belt cooperable with said means for securing said supporting member to the body, a body-engaging member including a pressure plate hingedly attached to said supporting member above the zone of said belt, and laterally adjustable body-engaging plates adjustably secured to said pressure plate, and resilient means between said pressure plate and supporting member in the zone of said belt, said resilient means being normally maintained under compression of said belt.

8. A truss, comprising a supporting member adapted to be secured to the body by a belt, a body-engaging member hingedly attached to said supporting member above the zone of said belt and resilient means between said body-engaging member and supporting member in said zone adapted to be maintained under compression by said belt.

9. In a truss, a supporting member adapted to be secured to the body of a belt, a body-engaging member including a plate hingedly attached to said supporting member, and body-engaging plates adjustably secured to said first mentioned plate, said plates being made of rigid non-absorbent material.

10. A truss, comprising a supporting member, means for securing said supporting member to the body, a body-engaging member hingedly attached to said supporting member above said securing means, and resilient means between said body-engaging member and supporting member adjacent the zone of said securing member.

In testimony whereof I have hereunto set my hand.

TAYLOR J. SMITH.
